UNITED STATES PATENT OFFICE.

ROBERT H. READ, OF SCHENECTADY, NEW YORK, ASSIGNOR TO GENERAL ELECTRIC COMPANY, A CORPORATION OF NEW YORK.

COMBINED CIRCUIT-BREAKER AND STARTING-RHEOSTAT.

SPECIFICATION forming part of Letters Patent No. 779,182, dated January 3, 1905.

Application filed October 28, 1903. Serial No. 178,809.

To all whom it may concern:

Be it known that I, ROBERT H. READ, a citizen of the United States, residing at Schenectady, county of Schenectady, State of New York, have invented certain new and useful Improvements in a Combined Circuit-Breaker and Starting-Rheostat, of which the following is a specification.

This invention relates to starting-rheostats for electric motors. It is customary to provide motor-circuits with an automatic circuit-breaker which opens both on a failure of current and on an overload in order to protect the motor from the injurious effects in the one case of a sudden rush of current when the circuit is established and, on the other hand, from damage possible when restarting after failure of voltage; but the former evil effect may be produced if the circuit-breaker is closed without first cutting in the resistance-coils. Hence it is very desirable to provide some means for compelling the resistance to be cut in before the circuit-breaker can be closed.

25 The object of my invention is to provide a device of the kind which is simple in construction and efficient and reliable in operation.

It consists of a circuit-breaker having a spring-opened bridging-piece or contact-arm automatically retained in the closed position and adapted to be automatically released both by the no-voltage coil and by the overload-coil. The operating-handle of the circuit-breaker is pivoted on the same stud as the contact-arm and is free to turn independently thereof, but can be clutched to it when it is desired to set the circuit-breaker. The clutch can be operated either mechanically or electrically, and in either case it is controlled by the switch-arm of a motor-starting rheostat arranged adjacent to the circuit-breaker, the construction being such that the rheostat-arm will operate the clutch only when said arm is brought to the "off" position.

45 In the accompanying drawings, Figure 1 is a front elevation of my combined circuit-breaker and rheostat. Fig. 2 is a top plan view of the same, and Figs. 3 and 4 are respectively similar views of a modification.

The parts are supported on a suitable panel, 50 of slate or other insulation, to which are secured the line-terminals 1 and 1^a. The circuit-breaker has the usual stationary spring-mounted contacts 2 and 2^a, adapted to be connected by the bridging-piece 3, insulated from the contact-arm 4, pivoted at 5 and urged away from said contacts by the coiled spring 6. A no-voltage coil 7 and an overload-coil 8 are arranged to trip the circuit-breaker detent and permit the spring to throw the contact-arm 60 out of engagement with the contacts 2 and 2^a in the usual manner. The details of this mechanism are well understood by those skilled in the art.

The circuit-breaker-operating handle 9 is 65 pivoted on the same stud as the contact-arm and turns freely thereon independent of said contact-arm. The opposing faces of the hubs of the handle and contact-arm are provided with coöperating clutch-teeth, so that when 70 the hub 9 of the handle is slid axially against the hub of the arm the two will interlock and the arm can be moved by moving the handle. The handle-hub has a circumferential groove 10, with which engages the forked end of an 75 elbow-lever 11, suitably fulcrumed in a standard 12, secured to the panel. A spring 13 causes the lever to keep the clutch normally open, as shown in Figs. 2 and 4.

The rheostat switch-arm 14 is pivoted at 15 80 and coöperates with the contact-buttons 16 of the rheostat. When this arm is moved to the off position after cutting all the resistance into the armature-circuit of the motor 17, it operates to move the elbow-lever and close 85 the clutch. Two ways of accomplishing this are shown. In Figs. 1 and 2 the switch-arm has a cam 18, which strikes one end of a bent lever 19 and moves it to the left, causing a fork 20 on the other end of the lever, which engages with the short end of the elbow-lever 11, to rock said lever on its fulcrum and throw the handle-hub against the hub of the contact-arm.

In Figs. 3 and 4 the switch-arm carries an 95 insulated blade 21, which closes a shunt-circuit containing an electromagnet 22, which when thus energized attracts the free arm of

the elbow-lever and closes the clutch. In either case the circuit-breaker cannot be set until the switch-arm 14 is brought to the off position. When the breaker is set, it latches automatically, and the switch-arm can then be swung to the left to cut out the resistance. After the lever 14 is swung from its off position the bent lever 19 drops or the magnet 22 is deenergized, allowing the clutch to open. If now the circuit-breaker goes off, it cannot be reset until the switch-arm is moved to the extreme right, which cuts all the resistance into the motor-circuit and then opens said circuit. It is therefore impossible for the attendant to set the breaker while the resistance is cut out. As shown, both the over-load-magnet 8 and the no-voltage magnet 7 act on the same arm, the windings being so proportioned that the no-voltage magnet normally overcomes both the retracting-spring and the over-load-magnet. Any other arrangement of these magnets by which either may trip the lever 4 under the desired conditions might of course be employed.

25 What I claim as new, and desire to secure by Letters Patent of the United States, is—

1. The combination, with an automatic circuit-breaker, of a rheostat, means for disconnecting the operating-handle from the movable contact of the circuit-breaker, and means controlled by the rheostat-arm for establishing a connection between the handle and mov-

able contact only in the off position of said arm.

2. The combination with a circuit-breaker, 35 of an automatic starting-rheostat, and means for connecting and disconnecting the handle from the movable contact of the circuit-breaker, said means being controlled by the rheostat-arm.

3. The combination with a circuit-breaker, 40 of a starting-rheostat, a clutch for connecting and disconnecting the handle of the circuit-breaker, and means for operating said clutch controlled by the rheostat-arm.

4. The combination with a circuit-breaker, 45 of a starting-rheostat, a clutch for connecting and disconnecting the handle of the circuit-breaker, a lever for operating said clutch, and means for actuating said lever controlled by the rheostat-arm.

5. The combination with a circuit-breaker, 50 of a starting-rheostat, a clutch for connecting and disconnecting the handle of the circuit-breaker, an elbow-lever for operating said 55 clutch, a cam on the rheostat-arm, and actuating connections between said cam and the lever.

In witness whereof I have hereunto set my hand this 26th day of October, 1903.

ROBERT H. READ.
